UNITED STATES PATENT OFFICE.

EZRA C. FITCH, OF WALTHAM, MASSACHUSETTS, ASSIGNOR TO WALTHAM WATCH COMPANY, OF WALTHAM, MASSACHUSETTS, A CORPORATION OF MASSACHUSETTS.

POCKET-WATCH.

1,084,880.

Specification of Letters Patent.

Patented Jan. 20, 1914.

Application filed May 6, 1913. Serial No. 765,764.

To all whom it may concern:

Be it known that I, EZRA C. FITCH, a citizen of the United States, and resident of Waltham, in the county of Middlesex and 5 State of Massachusetts, have invented certain new and useful Improvements in Pocket-Watches, of which the following is a specification.

The present invention relates to pocket 10 watches and has for its primary object to provide a watch which combines the advantages of the highest possible accuracy and of the least possible thickness.

The modern demands for watches embrace 15 two distinct qualities or characteristics. First, there is a proper and increasing demand for accuracy in watch performance. Concerning this, it may be said that while absolute accuracy is doubtless unattainable, 20 it is yet true that modern achievements have made so close an approach to it that very little more seems possible. But second, there is a corresponding feeling that while little remains to be achieved in the direction 25 of accuracy, there yet remains quite a field for improvement in the direction of beauty and convenience of form in which the pocket timepiece shall be made. A pocket watch may very appropriately combine 30 the merits and advantages of utility, beauty and convenience. While it is at all times a matter of convenience and often of necessity for a gentleman to carry a reliable timepiece, there are occasions when it is desired 35 to make it inconspicuous.

The attainment of the advantages of such convenience, beauty and utility is the object 40 of the present invention. This object is achieved by means of the improved construction of the combination between a watch movement and its case, of which the preferred form is exhibited in the drawings forming a part of this application, and is explained in detail in the following specification.

In the drawing, Figure 1 is a rear elevation 45 of a pocket watch in which my present invention is embodied, the watch being shown with the back cover of the case removed, representing approximately the 50 actual size of the watch. Fig. 2 is a central cross section of the watch drawn to the same scale as Fig. 1. Fig. 3 is a partial cross sec-

tion of the watch on a greatly enlarged scale.

I will first describe the details of construction shown in these drawings and then explain the principles and purposes underlying such construction.

The parts lettered *a* and *b* represent the 60 frame of a watch movement, the part *a* being the part which is ordinarily known as the pillar plate and sometimes as the bottom or front plate, and the part *b* representing the top or back plate or one of the 65 bridges which is secured to the pillar plate and contains the bearings for one end of the various arbors or staffs of the watch movement, which have their other ends supported in bearings in the pillar plate. As 70 my present invention does not require for its carrying out any change in the construction of the movement and movement frame, I have not shown these parts in any detail, merely showing enough of the movement 75 frame to indicate its position and size with relation to the case.

The case consists of the usual annular central member *c* commonly called the case center, the back cover *d* and the bezel *e* carrying the crystal *f*, the case center being provided with the usual annular ribs or shoulders *c*¹ and *c*² somewhat undercut on their outer sides to hold the back cover and bezel in place. In these respects there is no 85 difference between the case here shown and any ordinary watch case, and any of the known modes of attaching the cover and bezel to the case center may be utilized in a watch made according to my invention 90 without departing from the invention. The manner in which this case differs from the ordinary case is particularly in its thickness or width from front to back and particularly in the slight width in this direction 95 of the case center. In diameter the case is substantially the same as the standard or ordinary gentleman's watch.

It will be noted that the inner diameter of the case center is considerably larger than 100 the external diameter of the movement frame. Occupying the space between the movement frame and the case center is an annular frame *h* and a ring *i*. The former fits the pillar plate of the movement frame 105 and has a lip *h*¹ overlying the edge of the

pillar plate and against which the latter is clamped by the attaching screws h or by any other suitable means. The frame h also has a lip h^2 overlapping the inner circumference of the case center within the rib c^2 . The ring i fits easily around the top plate b or the equivalent bridges, and on its outer edge fits within the rib c^1 of the case center and bears against the face of the case center within such rib. The ring also has a flange i^1 extending toward the frame h to hold the inner circumference of the ring at the proper distance from the frame when the latter and the ring are secured together by the connecting screws l . There are as many of such connecting screws as may be required, three being usually sufficient. They pass through holes in the ring i and enter tapped sockets in the frame h . When the frame and ring are drawn together by these screws their outer edges grasp the inner portion of the case center between them and thus they are securely attached to the case center. As the movement frame is secured to the frame h by the means already described, such movement frame is thus securely connected with the case in a central position.

The dial of the watch is represented at m . This dial lies at the front side of the pillar plate and extends beyond the same to the rib or flange h^2 of the frame h , within which it is seated and is held in any common or suitable way, as by the studs n projecting from the inner side of the dial into sockets in the frame h and by set screws o passing from the periphery of the frame h into engagement with such studs. The studs and attaching screws are shown dotted in Fig. 3.

The ring i may be made plain or ornamental, as indicated in Fig. 1.

The case is provided with the usual pendant p shown in Fig. 1, containing the winding and setting stem of any appropriate character, the crown r of which is also shown in Fig. 1.

The means which I have above described for securing the movement in the case permits a standard movement of small diameter and correspondingly slight thickness to be mounted in a case having substantially the diameter of the standard gentleman's watch, while the slight thickness of such movement enables the case to be made much thinner than it has hitherto been possible to make such watches. Thus the advantage of thinness is secured while the advantage of accuracy is obtained by the employment of a standard movement, the small size and slight thickness of which permit the attainment of the desired thinness in the complete watch. At the same time the advantage of legibility is secured by the employment of the dial of large diameter, it being understood of course

that correspondingly longer hands are employed, the dial and hands extending to an amount greatly in excess of the radius of the movement itself. This improved form of construction secures the diameter and corresponding legibility of a large watch, such as that known commercially as the "12 size", together with the thinness of a "six 0" size, known commercially as "jewel series." Of course, in thus indicating the sizes and dimensions of the parts of the watch, I do not intend to be understood as limiting my invention to a watch of any particular proportions and dimensions, since I may combine a movement having even less diameter and thickness than that indicated with a case and dial of even greater diameter in order to secure the advantages of thinness, and legibility with accuracy, to an even greater degree than that indicated.

This improved watch is distinguished from watches heretofore produced in which a ring is employed as a part of the means for securing the movement in the case, in the following respects: That, whereas in such watches the movement is practically as large as the interior of the case center and the ring has very slight thickness (or radial width), in my improved watch the movement is much smaller than the case center, there is a wide annular space between the movement and the case center, and the annular frame, or annulus, h has a radial width substantially as great as this space, and therefore relatively great as compared with the radial width of the case center. Further, in my watch the movement is securely fastened in the annulus h independently of the fastening of the latter in the case; an entirely novel feature in watch construction, so far as I am aware.

I have not intended to restrict my invention to a watch of any particular shape, that is, to a watch having a circular outline rather than an outline of any other regular or irregular form. The term "annular" and the term "ring" as used in the foregoing specification and the appended claims in description of the case center and the members h and i are not intended to limit these parts or members to a circular form, but are intended to embrace any members having the same or equivalent functions, wherever their bounding outlines and whatever the position of the movement within the case. I consider that a watch which includes a case having any regular or irregular peripheral outline, a movement of smaller dimensions than the inner periphery of the case center, and an intermediate connecting member formed to fit internally within the case center and externally around the movement, whether the external and internal peripheries of such intermediate member are

similar or dissimilar, or are concentric or eccentric, is within the scope of my invention; and that a combination as above described including also a dial which extends beyond the movement in any direction is also within the scope of my invention, whatever may be the shape or outline of the dial.

What I claim and desire to secure by Letters Patent is:—

- 10 1. In a pocket watch, the combination with a movement frame of an annulus surrounding the front part of said frame and secured thereto, a case center surrounding said annulus, the latter having a flange overlapping the case center at one side, a ring surrounding the rear portion of the movement and having its outer edge overlapping the case center at the rear or opposite side, said ring occupying the space between the movement and the case center, and means for drawing said ring toward said annulus,
- 15
- 20

whereby to clamp the case center between the outer edge of the one and the peripheral flange of the other.

2. In a pocket watch, the combination 25 with a movement frame of an annulus surrounding said frame and secured thereto, a case center surrounding said annulus, a ring having a contour similar to that of the annulus, also surrounding the movement frame 30 and having its edge overlapping the case center at the opposite side to that over which the flange of the annulus extends, and means for drawing said ring toward said annulus, whereby to clamp the case center firmly between the ring and annulus.

In testimony whereof I have affixed my signature, in presence of two witnesses.
